APPARATUS FOR CONDITIONING HOT WIRE GAS DETECTORS

Louis F. Bonner, Houston, Tex., assignor, by mesne assignments, to Esso Research and Engineering Company, Elizabeth, N. J., a corporation of Delaware

Original application October 19, 1953, Serial No. 386,845, now Patent No. 2,713,010, dated July 12, 1955. Divided and this application March 22, 1954, Serial No. 417,908

3 Claims. (Cl. 23—255)

The present invention is directed to a method and apparatus for conditioning a hot wire gas detector. More particularly, the invention is directed to a hot wire gas detector and means for conditioning the electrical element for use in formation sampling and in mud logging operations where oil-emulsion muds are employed. In its more specific aspects, the invention is concerned with method and apparatus for removing combustible deposits from a hot wire gas detector used in logging operations in which oil-emulsion muds are employed.

This application is a division of U. S. Serial No. 386,845, filed October 19, 1953, entitled "Method and Apparatus for Conditioning Hot Wire Gas Detectors" for Louis F. Bonner now U. S. Patent No. 2,713,010, issued July 12, 1955, entitled "Method of Conditioning Hot Wire Gas Detectors."

The present invention may be briefly described as a method for conditioning a hot wire gas detector employed in formation sampling and in mud logging operations in which an oil-emulsion mud and/or formation samples are tested to determine the presence of hydrocarbons from subsurface earth formations. The specific feature of the invention is contacting the hot wire with vapors of a volatile oxygenated organic compound such as the aliphatic alcohols, aliphatic ketones and aliphatic ethers, these oxygenated compounds having a carbon chain in which there are no more than three carbon atoms. The vapors are then ignited whereby any deposits on the hot wire are removed by combustion of the volatile oxygenated organic compounds.

The present invention also is concerned with apparatus for use in mud and sample logging in which oil-emulsion muds are employed comprising a housing defining a chamber having an electrical element arranged in the chamber. This element becomes fouled with combustible deposits on use in said mud logging operations where oil-emulsion muds are employed. The apparatus comprises a container adapted to receive a body of a volatile oxygenated organic compound selected from the group consisting of the aliphatic alcohols, ketones and ethers having a carbon chain of no more than three carbon atoms. The container is provided with means for injecting air thereto at a lower point in the container below the surface of the body. A conduit is connected to the container at an upper point remote from the lower point and above the surface of the body. This conduit projects into the container and is partially or substantially enclosed by baffle members in the container which prevent entry of the liquid into the conduit. The conduit is connected to an introducing means for introducing the combustible mixture into the chamber. The chamber is provided with means for energizing the electrical element to ignite the mixture and burn off combustible deposits. The air injection means may comprise a plunger and a biasing means, such as a spring, for causing the plunger to inject air in the container. Likewise, the air injection means

2

may comprise a solenoid-operated plunger which is electrically energized.

The invention will be further illustrated by reference to the drawing in which:

5 Fig. 1 is an illustration of a preferred embodiment showing the biased plunger for injecting air into the container;

Fig. 2 is an illustration of a solenoid operated plunger;

Fig. 3 is a wiring diagram of the hot wire detector; and

Fig. 4 shows the application of the apparatus of the present invention to mud logging.

Referring now to the drawing and particularly Fig. 1, numeral 11 designates a hot wire detecting device which is provided with electrical leads 12 connected to a recorder or indicator 13 of the balanced-bridge type. The indicator 13 has a scale 14 and an indicating means 15 to show the deflection of the instrument. The indicator 13 is provided with electrical leads 18a and 18b for energizing the hot wire from a battery such as 86.

15 The apparatus includes a container 19 in which is arranged a body of the volatile oxygenated organic compound 20. The container is provided with an inlet pipe 21 which leads to a lower part of the container below the surface 22 of the body of volatile oxygenated organic compound. The pipe 21 is connected by a coupling 23 to a check valve 24 which, in turn, is connected by conduit 25 to a plunger mechanism generally indicated by the numeral 26 and including a piston or plunger 27, a plunger shaft 28 and a biasing means, such as spring 29, which normally urges the plunger 27 downwardly. The lower end of the spring 29 bears against the plunger 27 while the upper end is confined by an annular sleeve 30. The plunger mechanism generally indicated by 26 has openings 31' in end 31 through which the shaft 28 projects. The shaft 28 is provided with a shoulder 32. Arranged adjacent the shoulder 32 is a cam or eccentric 33 connected by means of a shaft 34 to a clock mechanism or suitable other energizing means.

20 Connected to the container 19 is a conduit 35 which projects into the upper part of the container 19. The projection of the conduit 35 in the container 19 is partially or substantially enclosed by baffle members 36 and 37 which serve to prevent entry of liquid in the conduit 35. The conduit 35 is connected to a check valve 39 for introducing gaseous mixture into the indicating element 11. The indicator element is provided with ports 40 to allow the gaseous mixture to circulate freely over the hot wire or detecting element and for withdrawal of the combustion products.

25 40 The container 19 is provided with a closure member 41 which is threadably connected by threads 42 to the container, the conduit 35 passing through the closure member 41.

45 The check valves 24 and 39 are constructed similarly and are comprised of spheres or balls 43 which are designed to seat against seats 44. The spheres 43 are biased against the seats 44 by means of a biasing means or spring 45 arranged on a spring member 46, the spring 45 and the spring member 46 being mounted on a plate 47 arranged in the check valves 24 and 39.

50 Referring now to Fig. 2 in which the air injecting means is a solenoid-operated plunger, the numeral 50 designates generally the solenoid-operated mechanism in which is arranged a plunger 51, provided with O-ring seals 51a and 51b, which is normally biased in an upward position by a spring 52. The plunger 51 is provided with a shaft 53 on which is arranged a shoulder 54. A closure member 55 through which the shaft 53 projects is threadably connected by threads 56 to the solenoid member 50, the shaft 53 being slidably sealed by an O-ring 57. Wound around the upper end of the member 50 is a solenoid winding 58 which is connected by electrical con-

nections 59 and 60 to a source of power illustrated by a battery 61. Arranged in the circuit is a solenoid switch 62 which is connected to a snap switch assembly 63 which carries a stroke adjustment assembly 63a and which has a projecting means 63b, the snap switch assembly 63a and which and the solenoid switch being connected by a spring 64.

The solenoid assembly 50 is provided with first and second air intake check valves 65a and 65b, respectively, having spheres 66a and 66b biased against the seats 67a and 67b by means of springs 68a and 68b. A bleeder control valve 69 is provided to fit against the seat 70 which is actuated manually by a valve wheel 71, the valve housing 72 being provided with a port 73. Thus bleeder valve 69 controls the rate of return of plunger 51 and, therefore, the time cycle of injection.

Referring now to Fig. 3, it will be seen that the hot wire gas detector is a Wheatstone bridge 85 having a platinum wire 80 arranged in a circuit. The Wheatstone bridge comprises the platinum wire 80, a fixed resistor 81, a balancing resistor 82 and a compensating element 83 being connected by means of electrical connections 12 to the recorder or detector element 11. The Wheatstone bridge, which is generally indicated by the numeral 85, is provided with a source of power, such as battery 86, and connected thereto by means of electrical connections 18a and 18b. An ammeter 89 is arranged in electrical connection 18a and is provided with ampere control means, such as a resistor 90.

The apparatus of the present invention may suitably be used in mud logging operations, such as illustrated in Fig. 4, in which a mud line 100 is connected to a drilling operation, not shown, and delivers mud to a mud pit, not shown. The mud line 100 is provided with a standpipe 101 which allows the mud to rise therein as a column 102 due to the pressure head. Above the mud column 102 in standpipe 101 there is a vaporous atmosphere 104 in which the indicator element 11 is arranged as shown. The standpipe 101 is provided with a closure member 103.

Carried through the closure member 103 are the electrical connecting means 12 leading to the recorder 13 which has been described. Also carried through the closure member 103 is a conduit 38 including the check valve 39 which is connected to the conduit 35. The electrical connections 12 may be carried either through the closure member 103 or through the wall of the standpipe 101. Baffle 105 diverts mud from the line 100 through the standpipe 101 and assures continuous mud supply to the system.

The device of the present invention works in the following manner with respect to Figs. 1 and 3:

For the purpose of this description, it will be assumed that the hot wire element 80 which may be a fine platinum wire having an overall coiled length of $1/4$ to $3/8$ of an inch has become fouled with deposits resulting from well logging operations. The device of Fig. 1 is connected to the indicating element 11 including a platinum wire 80 and air is injected into the container 19 by operating the shaft 34, as the eccentric or cam 33 rotates in the direction indicated by the arrow, the cam bears against the shoulder 32 raising the shaft 28 embracing the spring 29. As the cam or eccentric continues the rotation, the collar 32 is released allowing air to be forced downwardly by the plunger 27, the air being sucked or drawn through the openings 31' in member 31 past the plunger 27 as it is raised by the rotation of the cam. When the plunger is released from the high part of the cam, the plunger is forced downwardly and the air is forced through the deck valve 24 causing the sphere 43 to bear against the spring 45. The air bubbles upwardly through the body 20 of the volatile oxygenated organic compound and thence into the conduit 35, the baffles 36 and 37 prevent any liquid due to breaking bubbles or from entrainment from passing into the conduit 35 and thence through the check valve 39 into the indicator 11 into contact with the hot wire 80 which is energized by

electrical connections 18 and 18a by battery 86. As the combustible deposits are removed from the wire, the indicating means 15 will become deflected and then returned to zero.

The device of Fig. 2 operates in a similar manner to supply air to the container 19. With reference to Fig. 2 with the plunger down and the spring 52 compressed, the switch 62 controlling the solenoid is open allowing the plunger to be forced upwardly by the pressure of the spring. The speed of the retreating plunger is controlled by the opening and closing of the bleeder control valve 69 which allows air to be exhausted by the port 73. As the plunger shaft 53 approaches the top of the assembly 50, air is drawn in below piston 5, through second check valve 65b by the sphere 66b moving off seat 67b and the stroke adjustment screw 63a is then contacted and caused to rotate. As this adjustment rotates clockwise, spring 64 will move solenoid switch 62 into a closed position thereby actuating the solenoid again and pulling the plunger shaft 53 downwardly compressing the spring 52, air having been trapped below the plunger 51 on the upstroke of the plunger 51 which is then forced down causing air to pass through the first check valve 65a forcing the sphere 66a off the seat 67a. The operation with respect to Fig. 2 thereafter is similar to that of Fig. 1.

In the operation with respect to Fig. 3, the mud flowing through the mud line 100 will rise as a column 102 in standpipe 101 and provide a vaporous atmosphere 103.

30 The detector element 11 including the platinum wire 80 is in contact through ports 40 with the vaporous atmosphere. By energizing the hot wire, the presence of combustible vapors in the atmosphere 104 may be determined on the scale 14 by the indicating means 15.

35 When the hot wire 80 becomes fouled with combustible products, volatile oxygenated organic compounds are introduced by introducing means 38 as has been described and the combustible deposits removed from the wire 80. Thereafter the mud logging operation may be resumed, 40 the removal of combustible deposits being conducted periodically and automatically as occasion requires.

45 The present invention is particularly adaptable for use in mud logging operations where a hot wire gas detector is used and where the wire becomes fouled with deposits. This is sometimes encountered in mud logging where a normal drilling mud, such as an aqueous mud, is employed but more frequently is encountered where oil-emulsion muds are used. In fact, heretofore it has been substantially impossible to conduct mud logging operations where oil-emulsion muds have been used. Efforts have been made to remove deposits from platinum wires using hot wire detectors by injecting vapors of gasoline and light hydrocarbons into the detector element and then energizing the hot wire to burn off the deposits. This has been unsuccessful in that the long chain hydrocarbons either do not burn with a sufficiently hot flame or leave in themselves a deposit which interferes with the accuracy of the device.

50 In mud logging where a well is drilled with oil-emulsion mud, the hot wire gas detector rapidly becomes inoperative due to the coating formed on the element. Prior to the present invention, the remedy was to remove the element or either replace it or clean it by burning out using hydrocarbon vapors. As will be clear, this requires considerable time and had to be performed many times a day, such as possibly every 15 minutes. The present invention obviates this difficulty since the device of the present invention may be connected to the hot wire detector and automatically and periodically employed to condition the element without removing it from the gas collection chamber. Thus the cam, such as described in Fig. 1, may be run at a controlled speed by a suitable gear which may be variable from one revolution in 5 minutes to 1 revolution an hour and likewise with respect to the solenoid actuated embodiment.

While especially useful in operations involving oil emulsion muds, the present invention is also applicable to use in logging drill cuttings, examination of bottom hole and side wall cores, aqueous drilling mud, and any media which comes into contact with subsurface formations which may contain hydrocarbons.

The nature and objects of the present invention having been completely described and illustrated, what I wish to claim as new and useful and to secure by Letters Patent is:

1. A system for conditioning a gas detector comprising a detector housing having an electrical element arranged therein for igniting gaseous mixtures, an electrical circuit including a source of electrical energy and indicator means connected to said electrical element, said indicator means being adapted to indicate the conditioning of said electrical element, a closed container, a body of a volatile oxygenated organic compound selected from the group consisting of the aliphatic alcohols, ketones, and ethers having a carbon chain of no more than three carbon atoms located in said container, a first conduit having one end extending into said container to substantially below the surface of said body, a cylinder, means for admitting air to said cylinder, a plunger slidably arranged in said cylinder, biasing means positioned in said cylinder adapted to urge said plunger in one direction, energizing means operatively associated with said plunger adapted to periodically move said plunger against the urging of said biasing means, the other end of said first conduit

fluidly communicating with said cylinder, a first check valve positioned in said conduit adapted to permit fluid flow from said cylinder to said container and to prevent fluid flow from said container to said cylinder, a second conduit fluidly communicating the interior of said container above said body and said detector housing, a second check valve positioned in said second conduit adapted to permit fluid flow between said container and said detector housing and to prevent fluid flow between said detector housing and said container, and baffle means positioned in said container adjacent said second conduit adapted to prevent liquid flow into said second conduit.

2. A system as recited in claim 1 wherein said plunger energizing means is a clock actuated cam.

3. A system as recited in claim 1 wherein said plunger energizing means includes a solenoid.
